SHOE

William Virgil Wakeland, Rock Island, Ill., assignor to
The Servus Rubber Company, Rock Island, Ill., a corporation of Illinois

Filed Apr. 13, 1965, Ser. No. 84,760

Term of patent 7 years

(Cl. D7—4)

The essential features of my new design reside in the full line disclosure on the drawing.

I claim:

The ornamental design for a shoe, substantially as shown and described.
